PENCIL CLIP

Millard Comstock, Miami, Fla.

Application October 22, 1936, Serial No. 107,048

6 Claims. (Cl. 120—38)

This invention relates to attachments for pencils and particularly to an attachment for associating a rubber eraser therewith.

In my present invention I provide improved means for positioning a rubber eraser upon a pencil in a novel and convenient manner and in such a way that it may be readily and conveniently adjusted or renewed.

Other features and advantages of my improved construction will appear from a study of the following specification and the accompanying drawing wherein:

Fig. 1 is a perspective view of my invention associated with a pencil.

Fig. 2 is a longitudinal cross-sectional view through the associated pencil, eraser, and my novel means for supporting the eraser.

Fig. 3 is a transverse cross-sectional view taken on the line III—III of Fig. 2.

Fig. 4 is a detailed perspective view of one element of my new device.

Referring to the drawing, 10 designates a pencil which, in the present instance, is of the conventional wooden variety, but might be any form of similar writing instrument such as an automatic pencil, a pen, or the like.

My improved eraser holding means, in the form illustrated, comprises a pair of opposed elements indicated generally at 11 and one of these elements is shown in detailed perspective in Fig. 4. Each element 11 preferably comprises an arcuate central portion 12 whose radius is approximately the same as the pencil to which it is to be applied. The arcuate portion 12 terminates at its upper end in a substantially flat, somewhat circular portion 13, provided about its periphery with a series of tooth-like projections 14 which extend in a direction toward the pencil or other writing implement to which the device is intended to be applied.

The portion 13 is adapted to carry upon its outer face, advertising matter, a monogram, or any other desired indicia.

The arcuate portion 12 terminates downwardly in a portion 15 which is adapted to be employed as a clip for retaining the pencil in the pocket of the person using it. The arcuate portion 12 is provided at one of its lateral edges with a semicircular notch 16 and at its other lateral edge with a semicircular ear or projection 17. In this manner two identical stampings 11 may be employed in opposed relation to form a substantially tubular assemblage which is adapted to embrace the upper end of the pencil 10; with the semicircular projection 17 of one of the mem-

bers 11 resting in the semicircular notch 16 of the other member 11, and vice versa. The projections 17 and the notches 16 are so proportioned that there is normally some clearance between them when the device is in assembled relation.

A retaining or ring member 18 is provided for cooperation with the body of the pencil for holding the opposed members 11 in assembled relation upon the pencil.

It will be noted that the eraser holding portions 13 are of sufficient size to prevent their passage through the ring member 18. In assembling the device the ring member 18 is applied from the bottom and before insertion of the body of the pencil 10. This is accomplished by placing an eraser 19 between the opposed eraser holding portions 14 with the tooth-like projections 14 bearing against opposite sides of the eraser 19 and then sliding the ring member 18 over both clip portions 15, and over the bumps 20, one of which is struck out upon the tubular portion 12 of each element 11 and into approximately the position which it occupies in Fig. 1. After the ring member has been positioned about the arcuate portions 12 of the opposed members 11, the upper end of the pencil 10 is inserted between the members 11 against the resistance of the resilient pocket clip portions 15 hereinbefore described, with the bumps holding the ring member 18 in a predetermined position.

It will be noted from an inspection of Fig. 2 that each element 11 acts as a lever having its fulcrum against the inner periphery of the ring member 18. The force applied against the lower extremities of the clip portions 15 by insertion of the body of the pencil 10 between the two clip portions 15 acts to force the parts of the tubular portions 12 above the ring member 18, and the portions 13, toward each other in pencil and eraser gripping relation. A considerable mechanical advantage is obtained by this construction and insures firm gripping of the pencil by the members 11 against accidental displacement and at the same time forces the tooth-like projections 14 into the rubber eraser 19 to prevent dislodgement thereof excepting by removal of the pencil 10 from between the elements 11.

For the purpose of more clearly illustrating the relationship of the inner diameter of the ring 50 member 18 and the members 11 with respect to the body of the pencil, the cross sectional view, Fig. 2, is taken across corners of a hexagonal pencil, whereas in actual practice and in Figs. 1 and 3 55

the clip portions 15 bear against flats upon hexagonal pencils.

While a single specific embodiment of the invention has been illustrated and described, it is 5 to be understood that the invention which it exemplifies is not to be limited thereby excepting as defined in the appended claims.

What is claimed is:

1. An attachment for pencils comprising a pair 10 of elongated transversely arcuate members adapted for pivotal connection intermediate their ends with their concave surfaces toward each other and adapted to engage and support an eraser between them adjacent one end of the 15 device and adapted to be associated with a pencil by placing the body of the pencil between said arcuate members, and a surrounding sleeve for maintaining said elements in assembled relation.
- 20 2. An attachment for pencils comprising a pair of elongated clamping members having intermediate portions of arcuate cross section, resilient arm members at one end of each of the clamping members, and portions at the other 25 ends of said members for engaging and supporting a rubber eraser, and an encircling sleeve extending about said intermediate arcuate portions of said clamping members to urge said resilient arm members toward the pencil and 30 resultantly to urge said other ends of said members resiliently toward each other to clasp and engage the body of the pencil and said rubber eraser.
3. An attachment for pencils comprising a pair 35 of opposed elongated members adapted to engage opposite sides of a pencil, means pivotally

engaging said members intermediate their ends, means adjacent one end of said members adapted to engage an eraser and support it therebetween, resilient means at the other ends of said members to urge said eraser engaging means toward each other, and a surrounding sleeve for maintaining said members in pivotal engagement. 5

4. An attachment for pencils comprising a pair of opposed clamping members adapted to engage a pencil and an eraser and hold them in 10 fixed relation to each other, said members being pivotally engageable intermediate their ends, resilient means for urging said members into clamping engagement with said pencil and said eraser through said pivotal engagement, and a 15 surrounding sleeve for maintaining said members in pivotal engagement.

5. An attachment for pencils comprising a pair of opposed elongated members engageable with each other and adapted to be applied to a pencil 20 or the like with said members on opposite sides of said pencil and one end of each member projecting beyond said pencil to form opposed clamping members for supporting an eraser, said members terminating at their other ends in resilient 25 arm portions, and an encircling sleeve about said members for maintaining them in assembled relation.

6. An eraser holding attachment for pencils comprising a pair of elongated arcuate elements 30 pivotally connected intermediate their ends, means for supporting an eraser between said elements adjacent one end of the attachment, and a surrounding sleeve for maintaining said pivotal connection. 35
